(57) **CLAIM**

The ornamental design for a multiple frame and shelf combination, as shown and described.

DESCRIPTION

FIG. 1 is a front perspective view of a multiple frame and shelf combination;

FIG. 2 is a front elevation view of a multiple frame and shelf combination;

FIG. 3 is a rear elevation view of a multiple frame and shelf combination;

FIG. 4 is a right side view of a multiple frame and shelf combination;

FIG. 5 is a left side view of a multiple frame and shelf combination;

FIG. 6 is a top view of a multiple frame and shelf combination;

FIG. 7 is a bottom view of a multiple frame and shelf combination;

FIG. 8 is a rear perspective view of a multiple frame and shelf combination; and,

FIG. 9 is an environmental perspective view of a multiple frame and shelf combination.

The shade lines in the Figures show contour and not surface ornamentation.

The broken lines showing portions of the design in all figures are included for the purpose of illustrating environment and portions of the article that do not form a part of the claimed design.

1 Claim, 7 Drawing Sheets
